UNITED STATES PATENT OFFICE.

JAMES A. ANDERSON, OF KANSAS CITY, MISSOURI.

APPLIANCE FOR STEAMING COLLARS.

SPECIFICATION forming part of Letters Patent No. 595,752, dated December 21, 1897.

Application filed June 20, 1895. Serial No. 553,421. (No model.)

To all whom it may concern:

Be it known that I, JAMES A. ANDERSON, of Kansas City, Jackson county, Missouri, have invented certain new and useful Improvements in Appliances for Steaming Collars, of which the following is a full, clear, and exact description, reference being had to the accompanying drawings, forming a part thereof.

My invention relates to an appliance for steaming starched articles, particularly collars, to render them susceptible of bending easily without injury upon any lines desired.

Previous to my invention devices have been employed to moisten by the application of a liquid the fold-line of a starched article to render it flexible and therefore susceptible of bending easily, but there has never been to my knowledge an application of steam to starched articles for the purpose. By rendering such article flexible on the fold-line its life is lengthened, as it may be repeatedly bent without injury.

In order that the invention may be fully understood, I will proceed to describe it with reference to the accompanying drawings, wherein—

Figure 1 represents a side view of a steaming device embodying my invention. Fig. 2 represents a vertical section taken on the line 2-2 of the same, and Fig. 3 represents a collar applied operatively upon said steaming device preparatory to having its corner bent or turned back.

In the said drawings, 1 designates a shell or casing provided with a drip-cock 2 at its lower end. Said casing may be of the form shown, which embodies a pair of castings screwed together, as shown at 3, or may be of any other suitable or preferred form.

4 designates a pipe which communicates with a steam-supply at one end and with the upper end of said shell or casing. Said pipe is provided with a valve 5. Communicating also with said shell or casing, preferably at its upper end, is the outlet-pipe 6 for steam, and said tube is flattened or formed with an approximately fan-shaped nozzle, so as to provide a comparatively long and narrow passage 7. This fan-shaped nozzle may be of any preferred configuration, the configuration or form depending upon the article to which steam is to be applied. For bending back the corners of collars of the style 8, so as to have a triangular flap 9, a nozzle perfectly straight

and in length equal to the hypotenuse of said 55 triangular flap will be employed, as shown in Fig. 3.

In practical operation after the drip-cock and the valve 5 are opened the steam enters by way of the pipe 4 the upper end of the 60 casing. The condensed steam gravitates in the direction of the feathered arrows and escapes through said drip-cock, while the dry steam turns upwardly in the direction indicated by the unfeathered arrows and passes 65 up through the tube 6 and escapes by way of the comparatively long and narrow passage 7 of the fan-shaped nozzle. The collar or other article which is to be rendered flexible is now placed in the required position upon said nozzle, so that steam will be applied thereto in a thin line to soften the starch and render the collar susceptible of bending easily. The flap may now be turned back easily by hand or by passing the collar between a pair of opposing 75 rollers in the customary manner.

Having thus described my invention, what I claim as new, and desire to secure by Letters Patent, is—

1. An appliance for steaming collars and 80 other starched articles and rendering them flexible, and therefore susceptible of bending easily upon any desired line, comprising a shell or casing, a steam-supply pipe leading thereto, and a steam-escape pipe communicating with said casing and provided with a nozzle having a long and narrow passage 85 through which the steam escapes in a thin stream, substantially as set forth.

2. An appliance for steaming collars and 90 other starched articles, and rendering them flexible, and therefore susceptible of bending easily on any desired line, comprising a shell or casing provided with a drip-cock at its lower end, a valve-controlled steam-supply 95 pipe communicating with said shell or casing, and a tube communicating with the upper end of said shell or casing and terminating in a nozzle having a long and narrow passage 100 through which the dry steam escapes in a thin stream, substantially as set forth.

In testimony whereof I affix my signature in presence of two witnesses.

JAMES A. ANDERSON.
